UNITED STATES PATENT OFFICE.

EMORY WARD STEARNS, OF ROSLYN, NEW YORK, ASSIGNOR TO PARKER, STEARNS & COMPANY, OF BROOKLYN, NEW YORK, A CORPORATION OF NEW YORK.

BUTTON COLLET.

Application filed June 30, 1922. Serial No. 572,045.

To all whom it may concern:

Be it known that I, EMORY WARD STEARNS, a citizen of the United States, residing at Roslyn, in the county of Nassau 5 and State of New York, have invented certain new and useful Improvements in Button Collets, of which the following is a specification.

This invention relates to the manufacture 10 of molded rubber collets and particularly to the rubber collets of buttons of the kind extensively used in the clasps forming parts of garters and hose supporters. Such clasps commonly comprise metal loops and rubber 15 collets mounted on base plates provided with studs, posts or rivets which serve to secure the collets to the base plates. It sometimes happens that the strain of the loops on the flanged heads of the collets unduly bends 20 or breaks the flanges of the collets or loosens or pulls the collets off of the base plates, and it is the object of my invention to so strengthen the collets that this difficulty may be corrected.

25 In carrying out my invention I embed a cloth or fabric of suitable texture in the flanged head of the collet which serves to give to it such strength as to avoid all possibility of undue bending or breaking. 30 The cloth is so embedded in the collet that it not only reinforces or strengthens it as a whole but it gives the desired strength to that part of the collet which engages the under or inner side of the flange or head 35 of the post or posts which connects the collet to the base plate, thus insuring a permanent connection between the button members.

In order to manufacture the button collets thus reinforced I employ a sectional mold formed with a plurality of suitable recesses and provided with suitable pins or posts to give form to a plurality of collets and I place between two mold members a sheet of cloth and a sheet of unvulcanized rubber. The mold sections, the rubber, and the cloth are placed in a press and when pressure is applied, the mold sections are forced towards each other, the recesses are 50 filled, and the desired form is given to the articles. In this operation the cloth is embedded in the flanged heads of the collets around the central openings therein. When this operation is completed, the sheet of collets thus formed is vulcanized. The col-

lets are cut from the sheet by dies or other suitable devices and may be tumbled or otherwise finished.

In the accompanying drawings:

Figure 1 is a perspective view of one form of rubber hose supporter button collet made in accordance with my invention.

Figure 2 is another perspective view of the same collet.

Figure 3 is a sectional view showing portions of the mold members and indicating how a sheet of cloth and a sheet of rubber are inserted between the mold sections before pressure is applied.

Figure 4 is a sectional view showing the 70 mold sections moved towards each other and in the position they assume before the molding of the rubber takes place.

Figure 5 is a detail sectional view on an enlarged scale showing the appearance of the molded article after the completion of the molding operation.

Figure 6 is a perspective view of another form of hose supporter button collet extensively used.

Figure 7 is a perspective view of the same collet looking from a different angle.

Figure 8 is a detail sectional view of portions of mold members suitable for forming collets such as shown in Figures 6 and 7. 85

Figure 9 is a sectional detail view on an enlarged scale indicating how a collet is formed in a mold of the kind shown in Figure 8.

Figure 10 is a detail perspective view indicating how the collets when first molded are joined by a thin sheet of rubber and fabric. 90

Figure 11 is a perspective view with parts broken away, parts in section, and parts shown in dotted lines indicating how the 95 rubber collet shown in Figure 1 is attached to a base plate.

Figure 12 is a similar view indicating how the collet shown in Figures 6 and 7 is attached to a base plate.

Figure 13 is an enlarged detail view indicating how the soft rubber is forced during the molding and pressing operation through the meshes of the cloth.

In Figures 11 and 12 I have shown rubber button collets A and B applied to base plates C and D in the usual way. The collets are of the same form as those extensively used but differ from others in having cloth *a, b* embedded in their flanged heads. 105 110

In this way the flanged portions of the heads are greatly strengthened, undue bending of the flanges when employed in connection with the loops of hose supporters, is avoided and the separation of the collets from the posts is prevented. It will be observed by reference to Figure 13 that the rubber extends through the meshes of the cloth and binds together the material 10 on opposite sides of the cloth.

Two forms of button collets are illustrated. The method of manufacture is substantially the same, but the form of the molds is somewhat different.

15 To produce the collets shown in Figures 1 and 2 I may employ three mold sections or members E, F and G. The section E is recessed at e to give form to the outer portion of the heads of the collets and this

20 section carries posts or pins e' for producing the central openings in the collets. The posts carry collars e² adapted to form the recesses which receive the heads of the rivets as indicated at R in Figure 11.

25 Section F is recessed at f to give form to the inner or lower part of the collet heads and also at f' to give form to the collet shanks.

The section G is formed with holes g to 30 receive the outer ends of the pins e'.

The mold sections are in practice adapted to produce several hundred collets at one operation. To do this a sheet of cloth X and a sheet of unvulcanized rubber Y is

35 placed between two of the sections as indicated in Figure 3 and the mold sections are brought together and placed in a suitable press. When power is applied to the press, the pins e' are forced through the cloth and

40 the rubber (Figure 4) and then as soon as the section F is forced to its full extent toward the section E, the rubber is spread and made to fill the recesses in the manner indicated in Figure 5. It will be observed

45 that in this operation the whole sheet is pressed in such manner as to fill the recesses of the mold, material being taken from the sheet between the recesses. When the pressing operation is completed, the molded col-

50 lets are connected by a relatively thin sheet of material as indicated in Figure 5.

In the pressing operation, the rubber is forced through the meshes of the fabric in the manner indicated in Figure 13 and thus 55 the material on opposite sides of the fabric is firmly bound together.

The sheet of collets may be vulcanized in the usual way and the collets may be cut from the sheet by dies or other suitable devices and may be tumbled or finished in the usual way.

The oblong collets shown in Figure 12 and also in Figures 6 and 7 may be produced in a similar way but the form of the mold is somewhat different. In this case the sec-

tion H carries pins h to produce holes b' in the collets. The section I has openings i adapted to form the shanks b² and the lower parts of the heads of the collets and the section J has recesses j to form the heads or outer portions of the heads. The cloth sheet X and the rubber sheet Y are placed between the sections I and J in the manner indicated in Figure 8 and when pressure is applied, the recesses of the mold sections 75 will be filled and form given to the collets. A sheet carrying several hundred collets may be thus formed, a section of such a sheet being shown in perspective in Figure 10. The holes b' formed in the collets by 80 the pins h are adapted to receive headed posts S which connect the collets to the base plate D in the manner indicated in Figure 12.

The collets produced in the manner hereinbefore described are much stronger and more serviceable than those heretofore made, this result being largely due to the fact that the embedded cloth so surrounds the post hole as to strengthen that part of 90 the collet which extends under the head or flange of the post or posts which secures the collet to the base plate.

While I have shown and described my invention as embodied in collets for hose 95 support buttons, it will be understood that it may be applied to button collets or button members of other forms.

I claim as my invention:

1. A rubber button member having a 100 thick, narrow flange and having stiffening material imbedded in the flange and extending to the extreme outer edge thereof to add rigidity thereto.

2. A rubber button member having a thick, narrow flange and having fabric imbedded in the flange and extending to the extreme outer edge thereof to stiffen it.

3. A rubber button member having a thick, narrow flange and having fabric imbedded in the outer edge of the flange to stiffen it with the rubber extending through the meshes of the fabric.

4. A button comprising a base plate carrying a headed post and a flanged rubber button member having stiffening material therein held on the base plate by the post with the stiffening material extending under the headed portion of the post.

5. A button comprising a base plate carrying a headed post and a flanged rubber button member having fabric imbedded therein held on the base plate by the post with the fabric extending under the headed portion of the post and the rubber extending through the meshes of the fabric.

In testimony whereof, I have hereunto subscribed my name.

EMORY WARD STEARNS.
